PROJECTION HEAD FOR AN OVERHEAD PROJECTOR

Philip M. Field, 470 Ridgewood Road, Maplewood, N.J.

Filed Jan. 8, 1964, Ser. No. 78,119

Term of patent 14 years

(Cl. D61—1)

Fig. 1

Fig. 2

Fig. 3

Fig. 4

Fig. 5

FIGURE 1 is a front elevational view of a projection head for an overhead projector embodying my new design;

FIGURE 2 is a side, elevational view thereof;

FIGURE 3 is a rear elevational view thereof;

FIGURE 4 is a top plan view thereof, and

FIGURE 5 is a bottom plan view thereof.

The dominant features of my design reside in the portions shown in full lines.

I claim:

The ornamental design for a projection head for an overhead projector, as shown and described.
